UNITED STATES PATENT OFFICE.

CHARLES V. PIERSON, OF DULUTH, MINNESOTA.

WALL CONSTRUCTION.

Application filed March 16, 1923. Serial No. 625,480.

To all whom it may concern:

Be it known that I, CHARLES V. PIERSON, a citizen of the United States, residing at Duluth, in the county of St. Louis and State of Minnesota, have invented certain new and useful Improvements in Wall Constructions, of which the following is a specification, reference being had therein to the accompanying drawing.

10 This invention relates to wall construction and has particular reference to a hollow wall made up of concrete blocks laid one upon the other as is now commonly practiced.

From an architectural standpoint there is 15 a certain degree of monotony in the external appearance of a concrete wall constructed with the ordinary blocks now used for the purpose, and one object of my present invention is to employ a header block of 20 special design which when used in the construction of a wall as hereinafter described will produce a Flemish bond effect and eliminate the undesirable appearance of the ordinary concrete wall.

25 Still another object of the invention is to increase the dead air space intermediate the sides of the wall as much as possible, and to have that air space break the connection between the ends of the blocks, they being laid up in mortar as is common, it being 30 well known that heat and cold will penetrate through the mortar much more quickly than through the concrete.

Another object of the invention is to produce 35 a novel form of corner block so that the architectural design of the wall will not be broken at the corners thereof.

Still other objects and advantages of the invention will appear in the further description thereof, and referring particularly 40 to the accompanying drawing forming part of this application in which like reference characters indicate like parts:

Figure 1 is a side elevation of a portion 45 of a wall made up of my improved concrete blocks;

Figure 2 is a top plan view of the same, showing the improved corner blocks, and

50 Figure 3 is a plan view of the corner blocks adjacent those shown in Figure 2.

The stretcher blocks are illustrated at 1, and in the construction of a wall they are used in pairs, being spaced apart the desired distance thus providing air space there-between, and adjacent their ends is placed 55 the header blocks 2, which are of general

U-shape, the distance between their legs being equal to the distance between the stretcher blocks, so that the air space will be continuous and break the connection between 60 the header and stretcher blocks.

The header and stretcher blocks are thus alternated in the construction of the wall until the corner is reached, where I employ a special two part corner block, the part 3 65 of which is much similar to the header 2, except that one leg is slightly longer than the other, and the part 4 of the corner block is substantially L-shaped, the shorter side of which is equal to the width of the header 2. 70 Thus when the corner blocks are alternately laid as illustrated in Figures 2 and 3, the external appearance will be in accord with the appearance of the balance of the wall.

It will be readily apparent to those versed 75 in the art that these blocks as illustrated may be readily molded by pouring of the concrete, thus making a more impervious and durable block for such a wall, and one less liable to conduct moisture than a dry 80 block wall. Also there is a continuous vertical air space in this type of wall thus having all the advantages of a hollow tile wall, but being able to pour the blocks of concrete permits of much cheaper construction as will be obvious. The header blocks, when alternated in adjacent layers of the wall to furnish the Flemish bond effect, also serve as a 85 center bond for the stretcher blocks directly above and below same.

Having thus described my invention, what I claim and desire to secure by Letters Patent, is:

1. A hollow wall comprising spaced 95 stretcher blocks bonded by U-shaped header blocks, the legs of the header blocks being in contact with the ends of the adjacent stretchers.

2. A hollow wall corner construction comprising U-shaped and L-shaped corner blocks, and stretcher blocks, said stretcher blocks being arranged in spaced relation, said U-shaped blocks having one leg longer 100 than the other, the longer leg coacting with the inner stretcher and the shorter leg co-acting with the L-shaped blocks to complete the outer wall surface.

3. A hollow wall comprising spaced 105 stretcher blocks bonded by U-shaped header blocks, the cut-away portion within said header blocks forming a continuation of the space intermediate of the stretcher blocks.

4. A hollow wall comprising spaced stretcher blocks bonded by a header block having a cut-away portion therein, said cut-away portion forming a continuation of the space intermediate of the stretcher blocks.

5. A hollow wall corner construction comprising spaced stretcher blocks extending into the corner of the wall, a pair of substantially L-shaped blocks coacting with the ends of the stretcher blocks forming an L-shaped opening within the corner.

6. A hollow wall corner construction comprising four coacting blocks forming an L-

shaped space within said wall about the corner, the terminals of said space being unequal in distance from the corner.

7. A hollow wall corner construction comprising four coacting blocks forming an L-shaped space within said wall about the corner, the terminals of said space being unequal in distance from the corner, and said blocks being reversible in their assembled relation about the corner.

In testimony whereof I hereunto affix my signature.

CHARLES V. PIERSON.
